(57) **CLAIM**

The ornamental design for a brake tail light as shown and described.

DESCRIPTION

FIG. 1 is a front view of the brake tail light showing my new design;

FIG. 2 is a back view thereof;

FIG. 3 is a left side view thereof;

FIG. 4 is a right side view thereof;

FIG. 5 is a top view thereof;

FIG. 6 is a bottom view thereof;

FIG. 7 is a perspective view thereof; and,

FIG. 8 is another perspective view thereof.

The broken line in FIGS. 1, 3, 4, 5 6, and 8 depicts portion of the brake tail light frame that form no part of the claimed design.

1 Claim, 8 Drawing Sheets(56)
